United States Patent Office

Des. 197,115
Patented Dec. 17, 1963

197,115

BIB

Roy Clayfield, 19 E. Woods Drive, Huntington, N.Y.

Filed Apr. 24, 1963, Ser. No. 74,594

Term of patent 14 years

(Cl. D3—26)

Fig. 1

The essential features of my design are shown in the full line disclosure on the drawing.

I claim:

The ornamental design for a bib, as shown and described.
